(57) **CLAIM**

The ornamental design for a convector, as shown and described.

DESCRIPTION

Fig. 1.1 is a top-right perspective view of a convector in accordance with our new design;

Fig. 1.2 is a front plan view thereof;

Fig. 1.3 is a right-side elevational view thereof;

Fig. 1.4 is a back plan view thereof;

Fig. 1.5 is a bottom plan view thereof;

Fig. 1.6 is a first cross-sectional view thereof; and

Fig. 1.7 is a second cross-sectional view thereof.

The broken lines shown in the drawings are for the purpose of illustrating portions of the article and form no part of the claimed design.

1 Claim, 7 Drawing Sheets
